UNITED STATES PATENT OFFICE.

CHERUBINO D' IORIO, OF CINCINNATI, OHIO.

COAT.

1,177,688.

Specification of Letters Patent.

Patented Apr. 4, 1916.

Application filed July 31, 1914. Serial No. 854,384.

To all whom it may concern:

Be it known that I, CHERUBINO D' IORIO, a subject of the King of Italy, residing at Cincinnati, in the county of Hamilton and 5 State of Ohio, have invented certain new and useful Improvements in Coats, of which the following is a specification.

My invention relates to lay-down collars for garments; and the object is to secure a better and more permanent fit in such collars, to save labor in attaining that result, and to dispose of the material in the collar so that it may be joined to the other parts of the coat to better advantage, both as to 15 structure and appearance, especially where the material is cloth having a marked pattern, such as striped cloth.

My invention consists in the details of construction and arrangement as will hereinafter be more fully described and claimed:

In the drawings: Figure 1 is a detail of the outer piece of the collar as it is originally cut in making up a collar according to my invention; Fig. 2 is a detail of the inner piece which is incorporated in the collar, this piece being shown as it is originally cut; Fig. 3 shows the two pieces sewed together; Fig. 4 shows these pieces opened out and the seam pressed; Fig. 5 shows the pieces thus 30 sewed together with the padding and stiffening in place, ready to fold the sewed-together pieces thereover; Fig. 6 shows these sewed-together pieces thus folded over the padding and stiffening; Fig. 7 shows the interior of the top of a coat with my improved collar in place therein; Fig. 8 is a side view of the coat shown in Fig. 7; Fig. 9 is a rear view of said coat; and Fig. 10 is a front view of said coat.

Usually, in the construction of lay-down collars for men's and ladies' coats and similar garments, the entire "stand" or inner portion as well as the "leaf" or outer portion has been formed of one piece of material, these being folded along a line termed the "break" of the collar and the inner or "stand" portion being sewed to the inner parts of the coat while the outer or "leaf" portion is closed with the stiffening and padding, which latter generally becomes the under side of such a lay-down collar on a coat.

In order to cause a collar to fit the neck and shoulders of the wearer it is necessary, 55 in forming a collar of one piece, to laterally stretch both the "stand" and "leaf" in their

lower portions, thus distorting the texture of the cloth, and, if it is a patterned fabric, disarranging the pattern thereof. Furthermore, with any except the flimsiest material, it is impossible to provide enough stretching of these parts to impart the proper shape; and such stretching as is provided results in a loss of the proper shape due to rearrangement of the cloth fibers, this especially being manifested by a wrinkling of the outer part of the collar and a recession of the collar back from the neck of the wearer. Furthermore, with all coats or other garments heretofore constructed with 60 lay-down collars and lapels, there is a lack of continuity of direction of weave and pattern from the leaf of the collar to the lapel which is sewed thereto, or, which, in "shawl" collars is continuous therewith, 65 owing to the peculiar manner in which the one-piece collar must be cut from the cloth as related to the manner in which the lapel part must be cut from the cloth. If lapels and collar are continuous, the necessary 70 stretching and distortion has been even more excessive.

I overcome all of the above difficulties, not only by making up a structure to form the "stand" and "leaf" portions of the collar 75 by joining two pieces 1 and 2, but by so correctly shaping each of these pieces with respect to the other that, when they are folded or provided with the "break," they automatically correctly dispose themselves to 80 form a collar which will at once cling closely to the neck and shoulders of the wearer, as is so much desired, and continue to behave in this manner as long as the garment may be worn, due to the fact that there has been 85 no distortion of the fibers of the material in providing the correct shape for the collar. Furthermore, by properly relatively shaping the two parts 1 and 2, and in addition cutting them with proper regard to the direction of weave of the cloth and of the pattern of the cloth, when the cloth has a pattern, I am enabled to preserve the correspondence of the pattern in the leaf portion 90 of the collar with that in the back of the garment as best seen in Figs. 8 and 9, in a manner more perfect than has heretofore been attained, and also to make the weave, 95 and the pattern, if there is any, of the leaf portion of the collar continuous in direction 100 with that of the lapel at each side, as is best seen in Figs. 8 and 10.

For the purpose of most clearly illustrating the above advantages of my invention and of making it possible to more readily note the manner of disposing of the material from the time it is cut until it is incorporated in the finished garment, I have represented in the drawing a material of a marked striped pattern. Such illustration also readily makes manifest the advantages 10 in matching the patterns of the different pieces as above alluded to. The superiority of fitting qualities of my improved collar construction is best appreciated upon actual inspection of a garment in which it is incorporated and with the garment upon the wearer. Practically all illustrations of clothing indicate a perfect fit of the garment around the neck and shoulders, but, as is well known to practical tailors, such a perfect fit is very rarely attained, and is attained in greater or less perfection only by the expenditure of a great deal of labor in "busheling," after this part of the garment is otherwise completed. The vain attempts 20 to stretch the fabric in the lower parts of the "stand" and "leaf" portions of the collar to secure the desired fitting effect frequently result in tearing or damaging the fabric in these regions, and necessitating the ripping in 25 open of the collar and the insertion of new pieces of fabric. Those skilled in the art well know that the fitting of lay-down collars on a coat or similar garment may frequently require the labor of a tailor for several 30 hours.

By the use of my invention, the time of cutting, fitting and constructing a collar for a coat or similar garment is reduced to an average of one-half hour, and the tailor and wearer are assured that the collar will remain as fitted regardless of the kind of cloth used.

The larger outer piece 1, the major portion of which goes to form the outside or "leaf" portion of the collar, has its outer edge 3 approximating an arc of relatively large radius, flared in its terminal parts, while its inner edge comprises terminal portions 4 almost at right angles to a median radial line of the arc which the outer edge approximates, and a median portion 5 approximating an arc of relatively small radius. The piece is cut with the weave, and, if any, the pattern, running substantially parallel with the median radial line of the arc, as is indicated by the stripes in Fig. 1. The other piece 2 is substantially a segment with one edge 6 approximating an arc of such radius that when the other edge 7, 45 which is generally substantially straight, is brought along the part 5 of the edge of the other part 1 and the two pieces sewed together as shown in Fig. 3, and then flattened out, as shown in Fig. 4, with the seam 8 still substantially straight, the parts 4 of

the edge of the piece 1 will lie substantially tangent to the edge 6 of the segmental piece with said segmental piece held flat. Another detail which contributes to this result is the formation of the segmental piece 2 as well as the flared terminal parts of the outer piece 1, so that, when the two pieces are sewed together, as before described, the two-piece structure may be laid out as shown in Fig. 5, with the edge 3, the middle and major part of which originally approximated an arc of considerable radius, now approximates a straight line, while the edges 6 and 4, collectively, approximate an arc; the material, however, adjacent all of these edges, being somewhat buckled and only roughly approaching the disposition described, and as clearly shown in Fig. 5. With the structure thus disposed, the padding 9 and stiffening 10, cut and sewed together as usual, with their "break" 11 formed in them, have their substantially straight lower edges 12 and 13 laid along slightly inside the now approximately straight edge 3 of the two-piece outer structure. Then, when the part of the outer structure uncovered by this padding and stiffening structure is folded inward over the padding and stiffening structure, as shown in Fig. 6, and the aggregate structure 95 curved around the neck and shoulders, all of the buckling and wrinkling of both of the pieces 1 and 2 will immediately disappear. The collar is then sewed into the garment in the usual manner, as indicated in 100 Figs. 7 to 10, inclusive, and this will be accomplished without stretching or distorting any of the parts and without the necessity of any attention to such adjustment. This is manifest in the completed garment 105 by actual demonstration; and as was indicated in Fig. 7, in the appearance of the segmental piece 2, which practically retains its original segmental shape with the edge 7 substantially straight; and as seen in Fig. 110 10, where this edge 7 curves around the neck but does not curve upward or downward. Also, the curved edge 5 of the piece 1 will closely approximate its original condition 115 which it had as indicated in Fig. 1, as will also the curved edge 3, which now has been brought around under the edge 12 of the padding and stiffening structure, so that the material of the piece 1, adjacent to this curve becomes the lower edge of the leaf of 120 the collar, which must conform nicely to the back and shoulders.

On account of the almost total absence of distortion of the fabric, the stripes of the leaf portion of the collar will have practically the same direction in the back of the collar as do the stripes of the back 14 of the coat, as best seen in Figs. 8 and 9. Furthermore, owing to the disposition of the material in conjunction with the cutting and

fitting above described, these stripes of the leaf portion of the collar may be very closely matched with the stripes of the lapel 15 where the two pieces of fabric are sewed together by the seam 16, as seen in Figs. 8 and 10, where, as is demanded, the stripes of the lapels 15 are substantially parallel with the outer edge 17 of the lapel. The ends 18 of the piece 1 are closed in somewhat 10 agonally at the notch 19 of the collar, and the stripes in this terminal portion of the leaf of the collar adjacent to the notch will substantially coincide with the stripes of the lapel terminating at the notch, as shown in Figs. 8 and 10.

From the foregoing it will be seen that not only does my invention permit better fitting with less labor, but results in the production of a garment with a lay-down 20 collar with the pattern of the material more neatly disposed so that the garment presents a more attractive appearance.

Having fully described my invention, what I claim as new and desire to secure by Letters Patent is:

1. In a coat comprising a back and lapels, in combination with said back and lapels, a collar comprising an outer piece forming the "leaf" portion and part of the "stand" portion, and an inner piece forming the remainder of the "stand" portion, said outer piece being cut with an outer edge convex and of relatively great radius in its middle, and an inner edge with a middle part concave and of relatively small radius, the median radial line of the curve of this concave part being substantially in alinement with the median radial line of the curve of the convex outer edge, and with flanking 30 parts extending to said lapels, and said inner piece being cut with a convex edge, and a substantially straight edge, which latter edge is placed along the concave part of the inner edge of the outer piece, said pieces being 35 seamed together along said edges thus placed together, and said edges being substantially of the same length when thus seamed together, the "break" of the collar following a curved line approaching the seam of said edges at the middle, but diverging therefrom laterally, the convex edge of said inner piece and the flanking parts of the inner edge of the outer piece being, when the pieces are thus seamed together, substantially uniformly curved due to the relative 40 shapes of the edges thus seamed together, whereby, when said pieces are joined to the other parts of the coat, both of said pieces are smoothly stretched in their respective 45 positions in the collar when the collar is curved to conform to the neck.

2. In a coat comprising a back and lapels, in combination with said back and lapels, a collar comprising an outer piece forming the "leaf" portion and part of the "stand"

portion, and an inner piece forming the remainder of the "stand" portion, said outer piece being cut with an outer edge convex and of relatively great radius in its middle, and an inner edge with a middle part concave and of relatively small radius, the median radial line of the curve of this concave part being substantially in alinement with the median radial line of the curve of the convex outer edge and with flanking 70 parts extending to said lapels, and said inner piece being cut with a convex edge and a substantially straight edge, which latter edge is placed along the concave part of the inner edge of the outer piece, said pieces being 75 seamed together along said edges thus placed together, and said edges being substantially of the same length when thus seamed together, the "break" of the collar following a curved line approaching the seam of said edges at the middle, but diverging therefrom laterally, the convex edge of said inner piece being, when the pieces are thus seamed together, substantially uniformly curved due to the relative 80 shapes of the edges thus seamed together, both of said pieces being cut, as aforesaid, from a fabric with the general direction of the weave parallel with the median radial line of the curved edges, the material of said back having the weave running substantially parallel with the median line of the collar, and the weave of the material of said outer piece and of said lapels being substantially alined and continuous 85 in direction.

3. In a coat comprising a back and lapels, in combination with said back and lapels, a collar comprising an outer piece forming the "leaf" portion and part of the "stand" portion, and an inner piece forming the remainder of the "stand" portion, said outer piece being cut with an outer edge convex and of relatively great radius in its middle, and an inner edge with a middle part concave and of relatively small radius, the median radial line of the curve of this concave part being substantially in alinement with the median radial line of the curve of the convex outer edge and with flanking parts extending to said 90 lapels, and said inner piece being cut with a convex edge and a substantially straight edge, which latter edge is placed along the concave part of the inner edge of the outer piece, said pieces being seamed together along said edges thus placed together, and said edges being substantially of the same length when thus seamed together, the "break" of the collar following a curved line 95 approaching the seam of said edges at the middle, but diverging therefrom laterally, the convex edge of said inner piece and the flanking parts of the inner edge of the outer piece being, when the pieces are thus seamed together, substantially uniformly curved due to the relative 100 shapes of the edges thus seamed together, whereby, when said pieces are joined to the other parts of the coat, both of said pieces are smoothly stretched in their respective 105 positions in the collar when the collar is curved to conform to the neck.

4. In a coat comprising a back and lapels, in combination with said back and lapels, a collar comprising an outer piece forming the "leaf" portion and part of the "stand" portion, and an inner piece forming the remainder of the "stand" portion, said outer piece being cut with an outer edge convex and of relatively great radius in its middle, and an inner edge with a middle part concave and of relatively small radius, the median radial line of the curve of this concave part being substantially in alinement with the median radial line of the curve of the convex outer edge and with flanking parts extending to said lapels, and said inner piece being cut with a convex edge and a substantially straight edge, which latter edge is placed along the concave part of the inner edge of the outer piece, said pieces being seamed together along said edges thus placed together, and said edges being substantially of the same length when thus seamed together, the "break" of the collar following a curved line approaching the seam of said edges at the middle, but diverging therefrom laterally, the convex edge of said inner piece being, when the pieces are thus seamed together, substantially uniformly curved due to the relative shapes of the edges thus seamed together, both of said pieces and said lapels 110

115

120

being cut from a patterned fabric with the general direction of the pattern elements parallel with the median radial line of the curved edges, said back being of patterned fabric with the pattern elements running parallel with the median line of the collar, with the pattern elements of this piece and

the lapels substantially alined and continuous in direction.
